UNITED STATES PATENT OFFICE.

CHARLES JOSEPH RAMSBURG, OF EDGEWORTH, PENNSYLVANIA.

HUMIDIFIER.

Application filed January 5, 1926. Serial No. 79,415.

The present invention relates to humidifiers, and more especially to a humidifier for humidifying the atmosphere of inhabited rooms, such, for example, as a dwelling house.

During the winter the houses and offices in the northern part of the United States are usually maintained at a temperature of 70° F. or above. The result is that the humidity of the air is very low, approaching a desert humidity in dryness. While the outside air may have a humidity of 60 or 80 percent, when this air is heated to the usual house temperatures, the percentage humidity is decreased due to the heating of the air, because for the same absolute amount of water per unit volume, the percentage humidity decreases with the temperature.

The high temperatures and low humidities at which the American people maintain their houses are becoming to be recognized as seriously prejudicial to health. Various devices have been suggested to overcome this condition and supply moisture to the air, but such devices have usually been virtually valueless because they have not supplied a sufficient amount of moisture. Such devices as water pans in furnaces and water pans on radiators do not supply enough moisture, because in order to maintain the atmosphere in an eight or ten room dwelling house at a proper humidity in cold weather, several gallons of water should be evaporated per day. With the increased use of hot water or steam radiators for house heating the problem is particularly difficult, because there is no central supply of air as in the case of a hot air furnace which may be humidified and because pans or tanks of water placed on the radiators are ineffective and usually forgotten.

My humidifier is particularly designed to be put into houses having the heating plants already installed and will convert the extremely dry air of the ordinary house into properly humidified air.

I have found by experience that for the ordinary house, a complicated automatic hygrostatic control is unnecessary and that satisfactory conditions may be obtained with a very simple apparatus having its water feed manually controlled to give a small drip, say of about 50 to 100 drops of water per minute. This amount of water is sufficient to maintain the atmosphere in the

usual eight or ten room dwelling house at a humidity of about 40 to 50% and at a temperature of about 70° F. As is well known, if the humidity is increased to say 40, 50 or 60%, the atmosphere is not only more healthful to breathe, but the house will be comfortable at a lower temperature than where the humidity is low, say 10 to 20% which is not unusual in houses during the winter.

Referring to the drawings which illustrate the preferred embodiment of my invention,

Figure 1 is an elevation partially in section, through a portion of a house cellar showing the humidifier installed;

Figure 2 is a vertical section through the humidifier;

Figure 3 is an elevation of the humidifier taken at right angles to the section of Figure 2 and indicating its internal construction in dotted lines.

Referring to the illustrated embodiment of my invention, reference numeral 1 indicates generally the humidifier. This humidifier may be placed anywhere in a house or in an office such as being placed in one of the rooms. However, in the case of a dwelling house, it is preferably located in the cellar 2 and is connected by its flue 3 to discharge into one of the living rooms 4 of the house. As shown in Figure 1 the humidifier is supported on the cellar wall 5 at a convenient height.

I found that there is sufficient diffusion of air through the ordinary house so that a single humidifier discharging its humidified air into one of the living rooms on the first floor is sufficient to maintain the desired humidity throughout the house.

The humidifier comprises a chamber 6 which contains a hot plate 7 upon which the water drips and is evaporated and a gas burner 8 for heating the hot plate. The bottom of the chamber 6 is open and it is connected at its top to the flue 3 which serves as a chimney to assist in maintaining a good convection current of air through the humidifier chamber to carry off the humidified air. While it is preferred to employ a fairly long flue 3 particularly in cases where the humidifier is located in a cellar, a shorter flue might be used or the flue might be dispensed with in case the humidifier is located directly in the room whose atmosphere is to be humidified. It is preferred, however, to use the flue 3 in order to maintain an ac-

tive convection current and guard against down drafts through the chamber 6.

A small and regulated flow or drip of water is supplied to the top of the hot plate 7 through a drip valve 9 which may be either a needle valve or preferably a valve having a porous and adjustably compressible felt washer through which the water seeps. The valve 9 is connected to a water supply pipe 10. The drip from the valve 9 falls for a short distance through the open air where it can be readily observed and the number of drops per minute counted, into a cup 11 and through a feed pipe 12 to a point directly above the hot plate 7. The water may drip from the end of the feed pipe 10 upon the hot plate, although it is preferred to feed the water down by means of a wick which will prevent splashing of the water or the formation of small globules of water which might dance along and off the edge of the hot plate before evaporation. Such small dancing globules of water are familiar to anyone who has dropped water on a hot stove lid. In order to furnish a suitable wick feed, a small piece of wood 13 like a match or a tooth pick is inserted in the lower end of the pipe 11 and is supported by the hot plate. Preferably a small disc or septum 14 of asbestos paper is placed on the center of the hot plate below the water drip to insure the even spreading of the moisture without spattering or the formation of the dancing globules.

The hot plate 7 is preferably of the form shown in the drawings and consists of a flat central portion 15 surrounded by a downwardly depending fluted flange 16. Beneath the edge of the flange 16 is an annular overflow pan 17 having the U-shaped cross-section shown in the drawing. An overflow pipe 18 is provided for discharging excess water if it fills the overflow pan 17. The overflow pan 17 is supported within the chamber 6 by suitable brackets 19 on the chamber wall. The hot plate 7 is spaced above the overflow pan 17 by the supports 20 which allow a free space between the top of the pan 17 and the hot plate 7. The gas burner, 8, which is preferably a Bunsen burner, is supported by its supply pipe 21 which is secured at 22 through the wall of the chamber 6. The upper part of the burner 8 terminates at about the level of the top of the overflow pan 17 and discharges its flame into the concave lower face of the hot plate 7. The products of combustion pass up, heating the center of the hot plate and then spread out laterally and flow downwardly under the lower edge 16a of the flange 16 and then upwardly over the top of the hot plate and into the flue 3. There is, of course, a considerable amount of entrained air which passes around the burner 8 and around the overflow pan 17 and which is carried along to form a convection current which sweeps by the burner and over the top of the hot plate along with the gases of combustion, thus insuring a sufficiently large current of air through the humidifier 70 to insure a good distribution of the humidified air as it is discharged into the room. Moreover, since there is a considerable flow of air through the humidifier, the air discharged into the room does not need to be 75 as highly humidified as would be the case in a humidifier which did not have a considerable circulation of air through it. This obviates any danger of the deposit of condensed moisture in the room near the discharge of the humidifier.

Normally the hot plate is maintained at such a temperature and the flow of water is so regulated that the water is substantially all evaporated from the center of the 85 hot plate. However, if the flow of water is increased or the gas flame cut down, the water may flow out and into the troughs in the corrugated flange 16 where it is held and is further evaporated. If the water is 90 not all evaporated in the troughs of the plate flange, any excess will drip into the overflow pan 17 where it is subject to still further evaporation.

The overflow pan 17, with its U-shaped 95 cross-section, insures a rapid circulation of the products of combustion and entrained air under the edge of the flange 16, thus insuring a good heat delivery to heat such flange to cause evaporation of any water 100 collecting in its troughs, as it is well known that the absorption of heat by a surface is a function of the velocity of flow of a heating gas over the surface. The downwardly extending flange also directs the products 105 of combustion and heated air against the surface of water in the pan 17 in case it is filled with water, thus insuring further evaporation. The arrangement of the annular pan and the downwardly flanged hot 110 plate has been found to be very efficient in protecting the gas flame against accidental down drafts through the humidifying chamber. If down drafts occur, the downwardly and outwardly extending flange 16 115 tends to deflect them down through the annular space 23 between the walls of the chamber 6 and the outside of the pan 17 and to thus shield the flame of the burner 8.

The arrangement has also been found to 120 be very efficient as an evaporator. It is found that a humidity of 40 to 50% may be maintained in an eight to ten room dwelling house in freezing weather with a consumption of about 1 to 1½ feet of natural gas 125 per hour. It will, therefore, be seen that the expense of running the humidifier is negligible.

The products of combustion pass with the 130 entrained air through the flue 3 into the

room which is to be humidified. With a good burner 8 the burning gas is completely converted into water vapor and carbon dioxide, since the combustibles in the gas are 5 hydrogen and carbon. The amount of carbon dioxide from the burning of one to two feet of gas per hour is not at all objectionable. The water formed by the burning of the hydrogen of the gas, of course, contributes to the humidity, but more important still is the fact that the hot gases serve to mingle with and heat the entrained air passing through the humidifier and thus give a good circulation of heated air over the evaporating surfaces and into the room whose atmosphere is to be humidified.

The flow of a liquid such as water from the house supply pipes is more easily and accurately regulable than the flow of a heating gas. I therefore prefer to supply gas in excess of that required to evaporate the maximum amount of water to be used and to set the gas flame with a fixed adjustment, and to regulate the amount of moisture supplied by the humidifier by the water supply. This can be very readily regulated by means of the valve 9. The excess heat also serves to produce a good convection current of air through the humidifier. If desired, a 30 hygrometer may be employed to indicate the humidity of the air in the house, although this is not necessary since the frosting of the window panes in freezing weather is an indication of sufficient humidity. Ordinarily, a humidity of about 40 to 50% at 70° F. is satisfactory.

The tests of heating engineers show that there is a much larger infiltration of air into an ordinary dwelling house than is generally suspected, such infiltration serving to effect a complete change of air every few hours. Since the outside air in winter is cold and therefore when heated is very arid, a considerable amount of water is necessary 45 for satisfactory humidification and this may amount to several gallons a day in a fair sized dwelling house. Since my humidifier may be connected directly to a water supply pipe, sufficient water is supplied, which 50 is not the case where attempts have been made toward humidification by means of pans placed in furnaces or on radiators.

While I have specifically illustrated and described the preferred embodiment of my invention, it is to be understood that the invention is not so limited, but may be otherwise embodied within the scope of the following claims.

I claim:

1. A humidifier comprising a chamber, a 60 hot plate in the chamber having a flattened central portion and a downwardly extending flange at its edge spaced from the walls of the chamber to allow an air passage between the edges of the hot plate and the 65 walls of the chamber, a gas burner beneath the hot plate and discharging its flame against the central portion of the hot plate within the downwardly extending flanged edge, a shielding means spaced inwardly 70 from the walls of the chamber and also spaced downwardly from the edge of the flange on the hot plate, whereby the products of combustion are allowed to flow under the edge of the hot plate but down drafts 75 are directed away from the flame and through the space between the shielding means and the sides of the chamber, and means for supplying a small regulated flow of water onto the top of the hot plate. 80

2. A humidifier comprising a chamber, a hot plate in the chamber having a downwardly extending flange around its edge spaced from the walls of the chamber to leave an air passage between the edge of the 85 hot plate and the chamber walls, an overflow pan supported in the chamber and spaced from the sides thereof, said overflow pan having a U-shaped cross-section and located beneath the edge of the hot plate 90 flange to receive any water drip therefrom, a gas burner beneath the hot plate and arranged to discharge its flame against the central portion of the hot plate, the hot plate flange and overflow pan cooperating to cause 95 the flow of the products of combustion downwardly beneath the edge of the hot plate flange and into the open top of the overflow pan, and means for supplying a small regulated flow of water to the top of 100 the hot plate.

In testimony whereof I have hereunto set my hand.

CHARLES JOSEPH RAMSBURG.
